DESIGN FOR A FENDER GUIDE

Gustave F. Bahr, Fairfield, Conn., assignor to
Caseo Products Corporation, Bridgeport, Conn.,
a corporation of Connecticut

Application July 9, 1936, Serial No. 63,732

Term of patent 3½ years

To all whom it may concern:

Be it known that I, Gustave F. Bahr, a citizen of the United States, residing at Fairfield, in the county of Fairfield and State of Connecticut, have invented a new, original, and ornamental Design for a Fender Guide, of which the following is a specification, reference being had to the accompanying drawing, forming part thereof.

Figure 1 is a plan view of the top portion of the fender guide showing my new design.

Fig. 2 is a side elevation of the fender guide, a portion of the stem being broken away.

Fig. 3 is a front elevation of the upper portion of the same.

Fig. 4 is a back elevation of the same, a portion of the stem being broken away.

I claim:

The ornamental design for a fender guide, as shown.

GUSTAVE F. BAHR.
